DISPLAY CASE

Barbara B. Rickert, New York, N. Y., assignor to Laros Incorporated, Bethlehem, Pa., a corporation of Pennsylvania

Application August 6, 1956, Serial No. 42,505

Term of patent 14 years

(Cl. D80—11)

FIG. 1.

FIG. 2.

FIG. 3.

Fig. 1 is a front perspective view of a display case showing my design;

Fig. 2 is a rear elevational view thereof; and

Fig. 3 is an enlarged fragmentary view of the upper edge of the back panel of Fig. 1 showing the cruciform shape of the openings.

The entire back panel and both side panels of the display case, except for a narrow band around the edges thereof are made of grill work having the openings of cruciform shape, although the cruciform-shaped openings are only shown in small sections of the respective panels.

I claim:

The ornamental design for a display case, as shown and described.
